UNITED STATES PATENT OFFICE.

ALEXIS YACOUBENCO, OF KIEFF, RUSSIA.

STEAM-BOILER.

SPECIFICATION forming part of Letters Patent No. 340,183, dated April 20, 1886.

Application filed January 9, 1886. Serial No. 188,079. (No model.)

To all whom it may concern:

Be it known that I, ALEXIS YACOUBENCO, a subject of the Czar of Russia, and residing at Kieff, Russia, have invented certain new and useful Improvements in Steam-Boilers Arranged in Batteries and in their Furnaces Having Straight Flues; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

In the construction of steam-generators, and more especially in stationary generators, it has been the aim to so construct the generator as to present a maximum area or surface to the influence of the heat and products of combustion from the furnace. This has resulted in the ordinary generator, in which are arranged the fire-tubes for the passage of the heat and products of combustion on their way to the smoke-stack, also in what is called the "multitubular generator," which practically consists of a group of small boilers so arranged as to afford a passage between them for the heat and products of combustion. Other forms of generators have resulted also from this aim to increase the heating surfaces thereof.

The object of this invention is to construct a steam-generator offering a maximum heating-surface to the heat and products of combustion from the furnace with a minimum liability to explosion.

The further object of this invention is to provide more efficient means for heating steam-generators and economizing fuel.

To these ends the invention consists, first, in a steam-generator composed of two or more connected groups of small boilers or boiler-tubes arranged and connected in battery or series, substantially as hereinafter more fully described; secondly, in the combination, with one or more connected groups of steam-boilers or boiler-tubes arranged and connected in battery or series, of a steam-dome or reservoir common to all of the boilers of the group or groups for superheating the steam in the dome, substantially as hereinafter fully described; thirdly, in the combination, with one or more

connected groups of steam-boilers arranged and connected in battery or series, of a feeder common to all the boilers of a group and to the series of groups, substantially as herein-after fully described; and, lastly, the invention consists in certain details of construction, arrangement, and combination of parts, substantially as hereinafter fully described.

Referring to the accompanying drawings, which form a part of this specification, and in which like letters indicate like parts, Figure 1 is a longitudinal vertical section of a steam-generator embodying my invention. Fig. 2 is a transverse vertical section taken on line xx of Fig. 1. Fig. 3 is a similar view taken on line yy of said Fig. 1; and Fig. 4 is a horizontal transverse section of a portion of the structure in which the generator is contained, showing the arrangement of ducts for the products of combustion leading to a common chimney.

The number of groups of boilers or boiler-tubes arranged in battery or series will depend upon the capacity of the generator and the grate-surface on the one hand, and the temperature of the gases and products of combustion escaping into the smoke-stack.

I usually employ two groups of boiler-tubes, arranged in battery or series, one in front of the other; but when the temperature of the gases and products of combustion as they reach the stack from the second group of boilers or boiler-tubes reaches or exceeds 200° centigrade, then I employ three successive groups of boiler-tubes.

According to the capacity the generator is to have, I employ one or more boilers arranged consecutively—that is to say, tandem fashion—or one boiler or group of boilers behind the other.

In practice I have found that the diameter of the boilers when arranged in groups should not be less than about fifty centimeters in order to render them accessible for cleaning, and the length of such boilers or boiler-tubes will of course depend on the heating-surface required.

In the above drawings I have shown two groups of boilers arranged immediately above the furnace-grate G, and above and on opposite sides of the fire-bridge B, and consist-

ing of nine boilers; and the other, consisting of six boilers, is arranged in rear of the first group.

In practice I support the boilers in such manner as to give them a slight inclination, the boilers of the first group being inclined towards the front and those of the second group toward the rear of the structure or masonry M, that constitutes the housing of the generator. The boilers of each group are connected with one another by means of tubes t, either at both ends, or, preferably, at one end only, as shown.

When the boiler-tubes are connected with one another at one end only there is no resistance offered to their expansion and contraction under varying temperatures. This would, however, be the case when the boilers are connected at both ends by rigid tubular connections, and when so connected means are to be provided to permit the expansion and contraction referred to. This may be accomplished by employing telescopic connecting-tubes. It will, however, readily be seen that with the latter connection care must be had to maintain a tight joint.

By connecting the boiler-tubes with one another at one end only I am enabled to employ connecting-tubes of very thin sheet metal, comparatively, and protect the same against direct action of the heat by means of any suitable refractory material or by inclosing them in a sheet-metal casing. The heat and products of combustion pass from the furnace-grate G, between and around the boilers of both groups and in a straight line directly to the chimney C, in rear of the last group of tubes, through the parallel passages or flues f f f. (Shown in Fig. 4.) By means of this arrangement there is no interruption or sudden check to the flow of the gases and products of combustion on their way to the chimney C, thus securing a better draft, and consequently a more thorough combustion of the fuel.

Each boiler T is closed at one end by a removable lid, L', to afford access thereto for purposes of cleaning.

In the first group, the tubes of which project slightly beyond the front wall of the furnace, I form a tight joint between the contacting surfaces of the tubes and lids by means of any suitable packing; but the like surfaces of the second or third group, if a third one is employed, I form a tight joint, preferably by means of asbestos packing.

It is not absolutely necessary that the boilers should be of the same diameter. They may be of different diameters, as shown in Fig. 3, where the upper boiler is of greater diameter than the lower ones.

The feed-water may be introduced into either group of boilers. It is, however, well known that the majority of boiler-explosions are due to low water, and the introduction of feed-water which comes in contact with the

overheated boiler-surfaces, resulting in what is termed "flashing," and producing an instantaneous inordinate volume of steam, a pressure beyond that which the boiler can resist. For this reason I prefer to feed the water into that group farthest from the source of heat, or in the last group in the series.

The feeding of the water to the boiler-tubes is controlled automatically, and the feed mechanism is constructed and operated as follows: D, Fig. 1, is a vertical dome or chamber provided with a water-gage, D', in which chamber is contained a float, F, the upper end of the stem of which is connected with a crank, c, secured to the plug or stem of a valve or stop-cock in the feed-pipe P, through which the water is forced in the direction of the arrows by a pump or other suitable and usual forcing device, which I have deemed unnecessary to show, as these devices and the mode of operating the same are well known. The pipe P is connected with one or more of the lower boilers, preferably the lower central boiler, which is connected by tubes t' t' with the two boilers, on opposite sides thereof, as shown in Fig. 3. As the water reaches the upper boiler of the series, it passes therefrom by a short pipe, p, with which it is connected by a pipe, P', that extends to the front of the generator and there connects with branches p', that communicate with both of the lower boilers and the boilers T of the first group, or with the said lower boilers and the boilers T above them, or only with those immediately over the fire-bridge.

In practice I prefer to introduce the feed-water to all the boilers of the first group, which are most exposed to the direct action of the heat from the furnace for obvious purposes.

The float F in the float chamber or dome D is so arranged that the level of the water in said chamber will normally stand above the level of the highest end of the boiler with which the chamber is connected, and will have to rise considerably in the chamber before the float closes the stop-cock in pipe P, so that the level of the water can never fall below that of the highest end of the upper boiler of the second group, at which end the float-chamber D is arranged.

As the boilers of the first group, or that part thereof which is most exposed to the direct action of the heat, lie on a lower level than that of the end of the upper boiler of the second group, the water in said boilers of the first group can never fall so low as to expose unprotected surfaces to the action of the heat on the furnace. Should this, however, from some unaccountable cause take place and one of the boilers explode, it need not necessarily carry with it the destruction of the entire generator, nor would in any case such damages result as result in explosions of generators of usual construction.

The feeding of the groups of boilers may be further controlled by a hand-valve or stop-

cock, S, in pipe P, and by a like valve or stop-cock, S', in pipe P', as shown in Fig. 1. I am aware that automatic feeding devices operating substantially like the devices above described are not new, and I do not desire to claim these broadly or *per se*.

Above the structure or masonry M of the generator are arranged two steam-reservoirs, R R, though a single one may be employed according to the capacity of the generator. These reservoirs are connected by means of pipes r r with a transverse pipe, r', that is connected by suitable branches, r², with the upper set of boiler-tubes, T, of the forward group at their rear or higher end, as more plainly shown in Fig. 1, to convey the steam generated in the group of boilers to the said reservoirs, the connecting-pipes r r whereof lead from the bottom of the reservoirs to the cross-pipe r', and the two reservoirs are preferably connected together by a pipe or pipes, r³. Through each reservoir R extends a pipe, E, that has its initial within the passage for the gases and products of combustion of the generator at a point preferably intermediate of the first and second groups of boilers and its terminal within said passage at a point in rear of the last group of the boilers and in proximity to the chimney C. A portion of the heat from the furnace G may thus be conducted through the reservoirs, for the purpose of drying or superheating the steam therein, and the heat regulated by means of a damper, e, connected with a suitable operating-lever that extends outside of the inclosing structure of the generator.

To prevent unconsumed fuel that may be carried along the draft flues or passages, or ashes from being carried and deposited in said heating-pipes E, I cover their mouths with a reticulated guard—as, for instance, a basket or shield of woven-wire cloth or perforated sheet metal, e', as shown in Fig. 1.

H H are pipes rising from the rear ends of the reservoirs R R, through which and the pipe I, connected therewith, the steam, dry steam, or superheated steam is taken for use.

The float-chamber D is connected by means of a pipe, d, with the reservoirs R, to allow the steam which may form or collect therein to escape, and when the steam from the discharge-pipe is cut off, the pressure throughout the generator will be equalized by steam from the reservoirs entering the dome float-chamber and exerting its pressure on the water therein, as will be readily understood.

In order to economize heat, and consequently fuel, by preventing radiation, the masonry or inclosing structure for the generator is provided in its sides and roof with air flues or passages m' m². Those m' on half of the structure communicate with the outer air through a valved passage, M', Fig. 2, and those m², formed in the other half of the structure, with a like passage opening into the ash-pit at M², so that air more or less heated may be taken from below the grate. These flues or air-pas-

sages m' m² may be connected with the chimney C, if desired; but I prefer to connect the flues or passages m' by transverse passages m³, at or near the rear end of the structure, Fig. 1, with the passages or flues m', so that a circuit is established, having its initial communicating with the outer atmosphere and its terminal below the grate; hence, when the fires are lit the ash-pit or space below the grate may be entirely closed, and the air taken at M' may be caused to circulate from one side and on top of the structure M to the other side, and thence escape at M² in a heated condition to the grate, to supply the necessary volume of air to the fuel. The air being thus pre-heated by the waste heat from the furnace, promotes the combustion, and a saving in combustible is effected.

The chamber or ash-pit A, below the grate G, communicates by a valved opening or openings, a, with a chamber, A', that extends nearly the entire length of the structure below its arched sole or bottom M³.

In the rear wall of the fire-bridge B are openings b, provided with a damper, b', through which the heated air that passes from the conduits m² through M² into the said ash-pit may be admitted in rear of the fire-bridge and there mingle with the heated gases and products of combustion, a second series of openings, a', being formed in the sole or bottom M³ of the structure M, some distance in rear of the fire-bridge, preferably intermediate of the two groups of boilers, to supply heated air from chamber A' to the heated gases and products of combustion on their way to the stack, thereby effecting as complete a combustion of the fuel as is possible and utilizing all the heat resulting therefrom.

Another advantage derived from this construction lies in the fact that the air supplied to the fuel through M' may be taken from any desirable part of a factory or work-shop where pernicious gases are present from any source, and these may then be conducted to the furnace, to be there consumed and their deleterious influences destroyed.

By providing air-ducts in the walls and below the bottom or sole M³ of the inclosing structure of the generator, the said structure is protected from intense heat and will consequently last much longer than would be the case if the walls thereof were solid.

The lower tier of boilers of the last group of the series—that is to say, that group which is farthest from the source of heat—are provided with sediment-traps K, and connected by a valved pipe, k, with a trough, L, into which the sediment collected in the traps may from time to time be discharged.

By arranging the groups of boilers consecutively, and feeding in the water to the lower set of tubes of the group farthest from the source of heat, the impurities introduced will usually precipitate before they are carried to the upper tiers of boilers, and may by the

means described be readily discharged. The water, after reaching those groups of boilers more directly under the influence of the furnace-heat, will therefore be almost absolutely 5 free from sediment, and incrustations at the points where this is most undesirable and dangerous are thereby prevented.

The feed-water pipe P' , that connects the rear set or group of boilers with that or with 10 those in front of it, passes through one of the air-ducts—namely, that m , which is the widest and immediately above the arch or crown of the structure—and separates the series of air-ducts m' on one side of the furnace from the 15 series of air-ducts n' on the opposite side, and in the walls of said duct m are formed the communicating-passages m^3 , as shown in Fig. 1, like passages being formed in the walls of the other ducts at their rear ends. By means 20 of this arrangement the water coming from the rear group of boilers cannot be cooled on its way to the boilers of the other groups.

In view of the small diameter of the boilers 25 a comparatively light sheet metal can be employed in their construction.

My improvements, or at least the most essential parts thereof may be applied to existing steam-generators without great alteration of the inclosing structure.

30 What I claim is—

1. A steam-generator consisting of two or more connected boilers or groups of such arranged in battery, tandem fashion, or one behind the other, in a chamber common to all 35 the boilers or groups of boilers, substantially as and for the purpose specified.

2. A steam-generator consisting of two or more connected boilers or groups of such arranged in battery, tandem fashion, or one behind the other, in a chamber common to all of them, in combination with a furnace and chimney located, respectively, at opposite ends of 40 said chamber, substantially as and for the purpose specified.

45 3. A steam-generator consisting of two or more connected boilers or groups of such arranged in battery, tandem fashion, or one behind the other, in a chamber common to all of them, in combination with a furnace located 50 at one end of said chamber, a boiler-feeder located at and connected with the end of the boiler or group of boilers farthest from the furnace, and a chimney located at the end of the chamber opposite to that at which the furnace is located, substantially as and for the purpose specified.

4. The herein-described improvement in steam-generators, consisting of two or more connected boilers or groups of such arranged 60 tandem fashion, or one behind the other, in a chamber common to all of them, a non-interrupted passage for the heat and products of combustion extending in a straight line along and around said boilers from the furnace to 65 the chimney, and a non-interrupted air-circuit extending through the walls of said cham-

ber, having its initial open to the atmosphere and its terminal underneath the furnace-grate, substantially as and for the purpose specified.

5. The herein-described improvement in 70 steam-generators, consisting of two or more connected boilers or groups of such arranged tandem fashion, or one behind the other, in a chamber common to all of them, a non-interrupted passage for the heat and products of 75 combustion extending in a straight line along and around said boilers from the furnace to the chimney, a passage in the roof of the chamber connected with the different groups of boilers, and a passage or chamber below said boilers 80 in communication with the boiler-chamber and the ash-pit by valved passages, substantially as and for the purpose specified.

6. A steam-generator consisting of two or more connected boilers arranged in battery, 85 tandem fashion, or one behind the other, one or more of said boilers being arranged on an inclined plane, as and for the purpose specified.

7. A steam-generator consisting of two or more groups of connected boilers arranged in battery, tandem fashion, or one group behind the other, one or more of the series being arranged on an inclined plane, as and for the purpose specified. 95

8. In a steam-generator, two or more boilers or groups of boilers arranged in battery, tandem fashion, or one behind the other, a furnace located at one end of the series of boilers or groups of boilers, and a boiler-feeder 100 located at and connected with the end of the boiler or group of boilers farthest from the furnace and operating to feed all the boilers or groups of boilers, in combination with a heater for heating the feed-water as it passes 105 from one boiler or group of boilers to the other, substantially as described.

9. In a steam-generator, a furnace, two or more boilers or groups of boilers arranged tandem fashion, or one behind the other, and 110 a steam dome or reservoir common to all the boilers or groups of such, in combination with a heater operating to dry or superheat the steam in the dome or reservoir by means of heat derived from the furnace, substantially 115 as described.

10. In a steam-generator, an inclosing-structure for the boiler and furnace, in whose lateral walls and roof are formed air-ducts, a fire-bridge extending across the draft passage 120 or passages in rear of the furnace, an ash-pit below the furnace-grate, and an air-chamber in rear of the fire-bridge below the sole or bottom of the structure in communication with the ash-pit and draft-passages through valved 125 openings, the air-ducts in the walls and roof of the structure forming an air-circuit that has its initial in communication with the atmosphere and its terminal in the space below the grate, substantially as and for the purpose 130 specified.

11. In a steam-generator, the combination,

with one or more boilers or groups of boilers arranged tandem fashion, or one behind the other, and a steam dome or reservoir common to all such boilers, of a boiler-feeder consisting of a float operating a stop or valve in the feed-pipe and located in a float-chamber connected with the last boiler or one of the boilers of the last group of such of the series and with the steam-reservoir, said float-chamber

being arranged at a higher level than the highest level of the series of boilers, substantially as and for the purpose specified.

In testimony whereof I affix my signature in presence of two witnesses.
